UNITED STATES PATENT OFFICE

KARL S. HOWARD, OF ST. LOUIS, MISSOURI, ASSIGNOR TO GENERAL STEEL CASTINGS CORPORATION, OF GRANITE CITY, ILLINOIS, A CORPORATION OF DELAWARE

LOCOMOTIVE STRUCTURE

Application filed April 27, 1931. Serial No. 533,326.

My invention relates to railway rolling stock and consists in a novel construction and arrangement of a locomotive smoke box, live steam piping, and throttle valve.

In my co-pending application, Serial No. 533,325, filed April 27, 1931, I utilize a single pipe for conducting live steam from the super-heater header in the top of the smoke box downwardly to a connection in the cylinder saddle. A forked live steam pipe, formed integrally with the saddle, conducts the steam from the lower end of this pipe outwardly to the valve chambers. The throttle valve is mounted either within the saddle or in the lower part of the steam pipe in the smoke box. In this manner, the throttle valve is accessible from the outside of the lower portion of the locomotive and space is conserved within the smoke box to accommodate various appliances usually located therein and the usual openings in the smoke box wall for steam pipes leading outwardly to the valve chambers are eliminated.

The main object of the present invention is to retain many of the advantages secured by the structure illustrated in the above mentioned application and at the same time to make the throttle valve housing and a part of the live steam pipe integral with the smoke box structure.

I attain this general object and other more detailed objects in the construction illustrated in the accompanying drawings in which—

Figure 1 is a side view of the front portion of a locomotive showing the cylinder saddle and smoke box mounted thereon, the front end of the smoke box being omitted.

Figure 2 is a front front view of the same.

Figure 3 is a vertical transverse section taken on line 3—3 of Figure 1.

Figures 4 and 5 are sections taken on the corresponding section lines of Figure 2.

Figure 6 is a front view of a modified form of my invention.

Figure 7 is a partial side elevation of the same.

Figure 8 is a bottom view of the structure shown in Figure 7.

Figure 9 is a substantially horizontal longitudinal section on the line 9—9 of Figure 7.

In the drawings, 1 indicates the locomotive main frame including pedestal legs 2 and a front deck portion 3. The cylinder saddle, comprising main steam cylinders 4, valve chambers 5, and a smoke box support 6, is shown integral with the main frame, although any suitable construction of these parts may be adopted without departing from the spirit of the invention. Integral with the saddle 6 are exhaust steam passages 7 extending from each valve chamber 5 inwardly through the saddle and upwardly into the smoke box 8. Live steam passages 9 also extend from the upright passage 10, which projects up into the smoke box at one side of the saddle, to each valve chamber.

The smoke box, indicated in general by the Figure 8, includes a cylindrical outer wall 11 adapted to be secured to the front end of the boiler shell (not shown) and having an opening 17 in the top for the smoke stack and another opening 18 in its bottom portion for exhaust and live steam connections. A live steam pipe 12 is formed integrally with the wall 11 of the smoke box and connects at its bottom end with the upright passage 10 projecting through the saddle and at its top end with the super-heater header 13. A throttle valve housing 14 is formed in the pipe 12 and an opening 15 is provided in the smoke box wall for insertion of the valve mechanism and to permit access thereto. A partition 16 extends across steam pipe 12 adjacent opening 15 and is provided with a renewable valve seat 18a.

Steam pipe 12 corresponds in general with the curvature of the smoke box wall 11 and a portion 19 of the pipe also serves as a depressed portion of the wall, as shown in Figures 4 and 5. This portion 19 is indented from the remaining portions of the wall 11 to prevent the throttle mechanism from projecting too far out from the side of the smoke box and also to permit the application of lagging or heat insulation to the pipe 12. A plate (not shown) may be secured over this indented portion of the casting to retain the lagging in place and to form a continuation of the cylindrical outer surface of the smoke box.

The structure shown in Figures 6, 7, 8, and 9 corresponds with the form previously described except that housing 20 in live steam pipe 21 is elongated to provide for a plurality of valves 22 which are operated by a rod 23 extending longitudinally of the boiler into the locomotive cab. Steam pipe 21 is integral with the smoke box wall 27. Housing 20 has a plurality of openings 24 for insertion of valves 22 and to permit access thereto, and renewable valve seats 25 are mounted in partition 26 extending across pipe 21.

By the constructions described above, much of the labor and expense usually necessary, in installing steam piping within the smoke box is eliminated. Moreover, by the elimination of bolted or riveted connections between live steam piping and the throttle valve housing and the smoke box wall, the necessity of continual inspection and repair caused by bolts or rivets working loose is obviated.

Obviously, the preferred forms of my invention illustrated and described may be modified as to various details without departing from the spirit of the invention and I contemplate the exclusive use of all such modifications as come within the scope of my claims.

I claim:

30. 1. In a locomotive, a smoke box support, a smoke box including an outer wall mounted on said support, a live steam pipe extending into the top of said smoke box, and a single steam pipe integral with said outer wall and extending from said first mentioned steam pipe through said smoke box and in said support.
2. In a locomotive, a smoke box support having a single live steam passage extending through the top thereof, a smoke box mounted on said support and including an outer wall, and a live steam pipe formed integrally with said wall and connecting with said steam passage and extending into the upper part of said box.
3. In a locomotive, a smoke box support, a smoke box mounted thereon and including a curved outer wall, and a single live steam pipe following the curvature of said wall from a point in the upper part of said smoke box to a point near the bottom thereof and connecting with a live steam pipe projecting from within said support through the bottom of said smoke box.
55. 4. In a locomotive, a smoke box including a curved outer wall, and a live steam pipe integral with said wall and adapted to connect with a passage projecting up through the bottom of said smoke box, a portion of the wall of said pipe forming a portion of said outer wall.
60. 5. In a locomotive integral cast metal structure, a smoke box wall, a live steam pipe, and a throttle valve housing having an opening leading to the exterior of said wall.

6. In a locomotive integral cast metal structure, a smoke box wall, a live steam pipe, and a housing for a plurality of throttle valves, said housing having openings leading to the exterior of said wall. 70

7. In combination in a locomotive, an integral structure comprising a smoke box saddle, steam control chambers, and live steam passages extending inwardly from said chambers and merging in a substantially upright portion extending through the top of said support, and another integral structure including a smoke box outer wall and a live steam pipe, said pipe connecting with said upright portion in the support. 75

8. In a locomotive, a smoke box having an outer wall, a live steam pipe integral therewith, a portion of said pipe forming a portion of said wall and said latter portion having an opening therein into the interior of said pipe, and a throttle valve housing within said pipe and adjacent said opening. 80

9. In a locomotive, a smoke box having an outer wall, a live steam pipe integral therewith, a portion of said pipe forming a portion of said wall and said latter portion having openings therein into the interior of said pipe, and a housing for a plurality of throttle valves within said pipe and adjacent said openings. 90

10. In a locomotive, a smoke box having an outer wall, a live steam pipe integral therewith, a portion of said pipe forming a portion of said wall and said latter portion having an opening therein into the interior of said pipe, a throttle valve housing within said pipe and adjacent said opening, and a renewable valve seat mounted in said housing. 100

11. In a locomotive, the combination of a smoke box having an outer wall, a live steam pipe integral therewith, a portion of said pipe forming a portion of said wall and said latter portion having openings therein into the interior of said pipe, a housing for a plurality of throttle valves within said pipe and adjacent said openings, and a plurality of renewable valve seats mounted in said housing. 105

12. In a locomotive, a smoke box having an outer wall, a live steam pipe integral therewith, a portion of said pipe forming a portion of said wall and said latter portion having openings therein into the interior of said pipe and a partition wall within said pipe adjacent said openings, said partition wall having openings for throttle valves. 110

13. A locomotive smoke box having a curved outer wall, a live steam pipe having a portion of its wall forming a portion of said outer wall and corresponding with the curvature thereof, and a throttle valve housing integral with said latter portion. 125

14. In a locomotive, a smoke box having an outer wall, a live steam pipe integral therewith, a portion of said pipe forming a 130

portion of said wall and said latter portion having openings therein into the interior of said pipe, a partition wall within said pipe adjacent said openings, said partition wall having openings for throttle valves and renewable valve seats.

15. A locomotive smoke box having an outer wall, and a live steam pipe integral with said wall and extending from the top of said smoke box downwardly to an opening in the

10 bottom thereof.

16. In a locomotive, a smoke box having an outer wall, a live steam pipe on the inside of said box and integral therewith, and a throttle valve housing located intermediate the 15 ends of said pipe and integral with said pipe and wall and having an opening leading to the exterior of the latter.

In testimony whereof I hereunto affix my signature this 21st day of April, 1931.

20 KARL S. HOWARD.
